UNITED STATES PATENT OFFICE.

WALTER L. WILKS, OF WALLINGFORD, CONNECTICUT, ASSIGNOR TO
GEORGE M. HALLENBECK, OF SAME PLACE.

DESIGN FOR A HANDLE FOR SPOONS, FORKS, OR SIMILAR ARTICLES.

SPECIFICATION forming part of Design No. 33,680, dated December 11, 1900.

Application filed November 14, 1900. Serial No. 36,530. Term of patent 3 $\frac{1}{2}$ years.

To all whom it may concern:

Be it known that I, WALTER L. WILKS, of Wallingford, in the county of New Haven and state of Connecticut, have invented and produced a new Design for a Handle for Spoons, Forks, or Similar Articles; and I do hereby declare the following, when taken in connection with the accompanying drawing and the letters of reference marked thereon, to be a full, clear and exact description of the same, and which said drawing constitutes part of this specification and represents a face view of a handle for a spoon, fork, or similar article embodying my design.

15 This invention relates to a design for a handle for spoons, forks, and similar articles, and the design consists in the configuration and ornamentation as hereinafter described, and shown in the accompanying drawing.

20 As herein shown, the design consists of a handle tapering from its inner end outward, the taper from the inner end being very gradual to a point near the outer end, where it

expands, forming an enlarged outer end. The surface is ornamented by long scrolls A B, 25 one on each side, extending from the extreme inner end to the outer end, where they are enlarged and curve inward, as at C D, and between the ends of these scrolls is a pointed ornate tip E. Within the scrolls A B are 30 scrolls F G, one at each side, the upper ends H I of which curve inward, and the lower ends filling the space between the scrolls A B, the said scrolls forming a panel J.

I claim—

35 The design for a handle for spoons, forks, and similar articles, as herein shown and described.

In testimony whereof I have signed this specification in the presence of two subscribing witnesses.
